(57) **CLAIM**

We claim the ornamental design for a handle, as shown and described.

DESCRIPTION

FIG. 1 is a top, front and left side perspective view of a handle showing our new design;

FIG. 2 is a left side elevational view of the handle of FIG. 1, wherein the right side elevational view is a mirror image thereof;

FIG. 3 is a top plan view of the handle of FIG. 1;

FIG. 4 is a bottom plan view of the handle of FIG. 1; and,

FIG. 6 is a rear elevational view of the handle of FIG. 1. The broken line showing of the saw blade is for illustrative purposes only and forms no part of the claimed design.
